(57) **CLAIM**

The ornamental design for a frame for baby carriage, as shown and described.

DESCRIPTION

FIG. 1 is a perspective view of a frame for baby carriage showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a right side view thereof, in a folded position.

The broken lines in the figure drawings showing the wheels, trays, and frame members are included for the purpose of illustrating environment and form no part of the claimed design.
